UNITED STATES PATENT OFFICE.

FRED D. ACKERMAN, OF KENDALLVILLE, INDIANA.

AUTOMATIC ELECTRICAL CONTROLLER FOR AIR-COMPRESSORS.

No. 809,083.

Specification of Letters Patent.

Patented Jan. 2, 1906.

Application filed May 17, 1905. Serial No. 260,865.

To all whom it may concern:

Be it known that I, FRED DAVID ACKERMAN, a citizen of the United States, residing at Kendallville, in the county of Noble and State of Indiana, have made certain new and useful Improvements in Automatic Electrical Controllers for Air-Compressors, of which the following is a specification.

My invention is an improved apparatus for arresting automatically the operation of an air-pump when a certain desired pressure has been attained in a storage-tank with which the pump is connected.

The invention is particularly intended and adapted for use in connection with the air-pump and air-storage tank employed in trolley-cars for braking and signal purposes, but is capable of general application and use.

The general features and details of construction, arrangement, and operation of parts of my apparatus are as hereinafter described, and illustrated in the accompanying drawings, in which—

Figure 1 is a plan view of my improved apparatus, save a portion shown in section for illustration of the interior construction. Fig. 2 is a side elevation, save a portion in section showing the interior construction. Fig. 3 is a central longitudinal section of the two air-cylinders and valve-chest of the apparatus. Fig. 4 is an enlarged horizontal section of the valve-chest and valve. Fig. 5 is an enlarged vertical section on the line 5 5 of Fig. 2. Fig. 6 is in part an elevation and in part a section of the automatic releasing mechanism by which the electric circuit is broken and the operation of the air-compressor arrested, the parts being shown in the position occupied when the automatic switch is closed. Fig. 7 is also an elevation and section of the same parts shown in Fig. 6, the spring forming part of the releasing mechanism being shown compressed, as occurs just previous to the automatic snap action by which the electric circuit is broken. Fig. 8 is a diagrammatic view of the entire apparatus.

In Fig. 1 the numeral 1 indicates a flexible pipe which in practice connects an air-reservoir or storage-tank and a valve-chest 2, containing a slidable valve 3 of the well-known D pattern. The valve-chest 2 is in turn connected by a tube 4 with an air-cylinder 5. (See Fig. 2.) Within the cylinder 5 (see Fig. 3) is arranged a slidable piston 6, which is connected with a valve 3 by means of a rod 7,

passing through the aforesaid tube 4. From the opposite side of the piston 6 projects a rod 8, which extends beyond the outer side of the cylinder 5 and is provided with a collar 9 and a spiral spring 10, which intervenes between 60 said collar and the adjacent end of the cylinder 5, it being permanently attached to both. It is apparent that the spring, which is shown normally contracted in Fig. 1, resists movement of the piston 6 toward the end of the cylinder to which the spring is attached and is expanded by such movement, as indicated in Fig. 2. The valve-chest 2 is connected by a flexible pipe 11 and rigid pipe 11^a (see Figs. 1 and 2) with an air-cylinder 12, arranged adjacent to and in this instance below the primary air-cylinder 5. The cylinder 12 is longer than the cylinder 5, but is similarly provided with a slidable piston 13, having a rod 14, which projects through the right-hand end of 75 said cylinder and is permanently connected with a flat bar 15, which slides in vertical slotted guide-posts 16. (See Figs. 1 and 2.) Between the piston 13 of cylinder 12 and the right-hand end of the latter is arranged a spiral spring 17, which encircles the rod, as shown, and is compressed when the piston moves to the right.

The aforesaid flat bar 15 passes through a cylinder 18, which is movable thereon and arranged between the two supporting-posts 16. Within the said cylinder is arranged a spiral spring 19, that encircles the bar 15 and is located between the right-hand end of the cylinder and a disk 20, placed adjacent to a stop-pin 21. On the left-hand end of the cylinder 18 is arranged an electrical switch member 22, consisting of a bar (see Fig. 1) adapted to enter between spring-contacts 23, the latter being in the form of brackets secured to the base upon which the posts 16 are fastened. The switch members 23 are connected by wires 24 with posts 25, which are in turn placed in circuit with a generator G and a motor M, a hand-switch S being also placed 100 in the same circuit. The motor M is connected with an air-pump, which is in turn connected with the air-tank to which the flexible pipe 1 is in practice attached.

A locking and automatic trip mechanism is 105 applied in connection with the slidable cylinder 18. The construction of the same is as follows: On the upper side of the cylinder is placed a metal bar having semicircular depressions 26 located near its ends. Alongside 110

the cylinder (see Figs. 2 and 5) is secured a vertical bracket or bent arm 27, carrying a vertical tube 28. Within this tube a rod or plunger 29 is adapted to slide, the same having a lateral pin 30 working in a vertical slot in the tube 28, so that the rod is prevented from rotating. The lower end of the rod is provided with a roller 31, which is adapted to seat in the depressions or cavities 26, before referred to. A cylindrical screw 32, having a milled head, is applied to the upper end of the tube 28, which is screw-threaded internally at that point. Between the said screw and the slidable plunger 29 is arranged a spiral spring 33. It is apparent that by rotating the screw 32 the pressure of the same upon the spring 33 and the compression of the latter may be regulated, as desired, with the corresponding effect of varying the pressure of the roller 31 in the depressions 26 of the cylinder 18.

As illustrated in Fig. 4, the D-valve 3 is held to its seat by a spring 34. An exhaust-port 35 is provided in the air-chest 2 adjacent to the port 36, that communicates with the pipe 11, which connects the air-chest with the lower air-cylinder 12.

Let it be supposed that the switch 22 is closed and that the motor is operating the pump to compress air. The valve 3 would then be, as shown in Fig. 4, connecting the left end of the cylinder 12 to the exhaust through ports 36 and 35. There being no pressure at the left of piston 13, the spring 17 would be fully expanded. As the air is compressed the piston 6 is gradually moved to the right against the tension of the spring 10, carrying valve 3 with it. When the pressure is sufficiently great, the port 26 is disconnected from the port 35 and connected to the interior of valve-chest 2, as shown in Fig. 1. Thereby air is admitted to the left of the cylinder 12, forcing piston 13 to the right against the pressure of spring 17 and compressing spring 19 until said latter spring overcomes the retaining influence of spring 33 and latch 31 and opens switch 32 with a snap action, whereby operation of the motor and air-compressor is arrested. Fig. 7 illustrates the compression of the spring 19 in casing 18 just previous to release of the latter from the spring-actuated latch 21, and Fig. 2 shows the position of said casing after such release. As air is drawn off from the storage-tank the air-pressure falls in chamber 2, the spring 10 gradually moves piston 6 and valve 3 to the left, so as to cover ports 35 36, or at minimum pressure disconnecting port 36 from valve-chest 2 and connecting it to exhaust-port 35, so that air escapes from cylinder 12 and piston 13 therein moves to the left, the switch 22 is closed, and the motor operates the pump to compress air again. This cycle of operation continues to maintain the pressure between certain maximum and minimum limits, which are determined by the adjustment

of spring 10. It will be understood that when the piston 13 of cylinder 12 thus resumes its normal position (shown in Fig. 6) the slidable casing 18 and its contained spring 19 are also drawn back to normal position by engagement of the pin 21 of bar 15 with the adjacent head of said casing. In this movement the spring 19 simply slides with the casing and has no function save in producing the automatic snap action before described.

Having thus described my invention, what I claim as new, and desire to secure by Letters Patent, is—

1. The improved automatic controller for the purpose specified, comprising a valve-chest 80 and valve, an air-cylinder and a slidable piston contained therein and connected with said valve, a spring for opposing the movement of the piston in one direction, a second air-cylinder having a spring-pressed piston, an 85 air-conductor connecting such second cylinder with the valve-chest, a slidable bar connected with the last-named piston, a casing applied to and slidable on said bar, a spring contained within the said casing and applying pressure 90 between it and the bar, an electrical switch one member of which is connected with the casing, and spring locking and release mechanism connected with the casing for holding it normally immovable and the switch normally 95 closed until a certain predetermined air-pressure is accumulated, substantially as described.

2. The improved controlling apparatus for the purpose specified, comprising two air-cylinders and pistons therein having springs 100 for opposing movement in one direction, an air-chamber having a slidable valve which is connected with one of said pistons, a pipe connecting the air-chamber with a second cylinder, and an automatic locking and releasing 105 mechanism connected with the piston of the second cylinder and comprising a slidable bar, a device that is slidable on said bar and provided with abutments or shoulders, a spring arranged between said device and a projection on said bar, and a spring-pressed latch adapted to engage with and automatically release said device, substantially as shown and described.

3. In a controller for the purpose specified, 115 the combination with an air-cylinder, a piston slidable therein, a slidable bar extending therefrom and a guide in which said bar works, a casing applied to such bar and slidable thereon, a spring interposed between one portion of such casing and a stop on the bar, the casing having a top portion provided with depressions at opposite ends, a locking and releasing mechanism comprising a spring-actuated plunger having at its free end a 120 roller adapted to enter said depressions and thus lock the casing until the pressure of the plunger-spring is overcome, and a switch included in a motor-circuit and adapted to be broken when the air-pressure reaches a cer- 125

tain predetermined degree and the locking mechanism releases the cylinder which it engages, substantially as described.

4. In a controller for the purpose specified, 5 the combination with an air-cylinder and means for connecting it with an air-storage tank, of a piston which is slidable in said cylinder, a spring applied thereto for opposing movement in one direction, a bar connected 10 with the piston and slidable therewith, a casing applied to the bar and slidable thereon, a spring inclosed by the casing and arranged between one end thereof and a stop on the bar, a casing having on its upper side engaging shoulders, a locking and releasing mechanism comprising a vertical tube having a

slot in its lower side, a plunger slidable in the tube and having a lateral pin working in said slot, a roller journaled in the lower end of the plunger and adapted to engage projections arranged on the casing and spaced apart, a spring pressing on said plunger, a screw for adjusting the tension of the spring, and a switch included in an electrical circuit and adapted to be instantaneously parted when 25 the tension of the spring of the locking mechanism is overcome, substantially as described.
